(57) **CLAIM**

The ornamental design for an inkjet printer, substantially as shown and described.

DESCRIPTION

FIG. 1 is a perspective view of an inkjet printer in accordance with the present invention;

FIG. 2 is a front elevational view thereof;

FIG. 3 is a rear elevational view thereof;

FIG. 4 is a top plan view thereof; and,

FIG. 5 is a right side elevational view thereof the left side elevational view being a mirror image.

The dashed line showing of a potential fixed sheet feeder in FIGS. 1, 2, 4, and 5, is for illustrative purposes only and forms no part of the claimed design.

1 Claim, 4 Drawing Sheets

FIG.2

FIG.3
